(57) **CLAIM**

The ornamental design for a decorative fitting for a vehicle, as shown and described.

DESCRIPTION

FIG. 1 is a top perspective view of a decorative fitting for a vehicle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom perspective view of a decorative fitting for a vehicle.

In the drawings, the dot-dash lines represent boundaries of the claim and form no part of the claimed design.

1 Claim, 8 Drawing Sheets
